STOCKING

Jon Wallner, Jr., Clinton, Tenn., assignor to Magnet Mills,
Inc., New York, N.Y., a corporation of Delaware

Filed May 20, 1965, Ser. No. 85,379

Term of patent 14 years

(Cl. D47—7)

Fig. 1.

Fig. 2.

FIG. 1 is a side elevational view of a stocking showing my new design, the side opposite being a mirror image thereof; and

FIG. 2 is a fragmentary scale-wise showing of the decorative portion of the stocking.

I claim:

The ornamental design for a stocking, as shown and described.
